UNITED STATES PATENT OFFICE.

GEORGE CROUCH, OF NEW YORK, N. Y.

TRUNK.

SPECIFICATION forming part of Letters Patent No. 339,621, dated April 13, 1886.

Application filed January 7, 1886. Serial No. 187,863. (No model.)

To all whom it may concern:

Be it known that I, GEORGE CROUCH, of New York city, in the county and State of New York, have invented a new and useful Improvement in Trunks, of which I declare the following to be a full, clear, and exact description, reference being had to the accompanying drawings, and to the letters and figures of reference thereon, which form a part of this specification.

The present invention has for its object to more securely and certainly fasten the walls of a trunk together in the process of manufacturing the trunk; and it consists of the devices hereinafter described and claimed.

In the accompanying drawings, Figure 1 is a perspective view of a trunk-box having my improved fastening devices. Fig. 2 shows a modification of the fastening device.

A A A are the inclosing-walls forming the trunk, being the ends, sides, and bottom of the body of the trunk, and the ends, sides, and top of the lid of the trunk. Heretofore these walls, where any two of them meet and form a joint, have been simply nailed together, or have in addition been secured by rigid metallic angle-pieces wholly on the outside or wholly on the inside of the trunk, the two walls meeting and touching each other along their entire length or width. Under the ordinary strains of use the walls of the trunk under these circumstances are liable to bulge inward or outward, moving sidewise against the hold of the nails, and moving inward or outward away from the metallic angle-pieces, thereby starting and loosening the joint. My improved fastening avoids this liability.

B B are the fastening - strips. They are made of stout canvas or of other fibrous and sufficiently strong and durable material. They are of any desired length, width, and thickness, so long as they are capable of being combined with the walls of the trunk, as herein-after described.

Fig. 1 shows in detail the method of this combination. A A are, say, the end vertical wall of the trunk, and the bottom horizontal wall of the trunk. The fastening-strip B is placed between these two walls at their line of joining, as shown in the drawings. One end of the strip is then securely fastened by riveting or otherwise to the inside or upper

surface of the bottom wall of the trunk, along which it lies, and the other end, after being drawn taut, the two walls being held in 55 place, is securely fastened by riveting or otherwise to the outer surface of the end wall of the trunk, along which it lies. A second fastening-strip is placed in the same way between the same two walls and alongside of 60 the first; but its inner end is securely fastened to the inner surface of the end wall, and its outer end is securely fastened to the outer surface of the bottom wall of the trunk. More than two fastening-strips may be used at one 65 joint, as desired, and it is preferable to nail the walls together also, and metallic angle-pieces may also be used to any extent. A groove or seat for the strip B may, if desired, be cut in the wall of the trunk at the position 70 where the strip is to be placed between the two walls, and of the thickness of the strip, in order that the joint between the two walls may be a tight one along the rest of its length. Each joint of the trunk is treated as described 75 above. The covering and lining of the trunk are then applied in the usual way, covering the strips B from sight, and also serving to secure them in place.

It is an advantage of my improvement that 80 the strain upon the fastening-strip is exactly and always in the direction of its length, in which direction it is strongest, and because of its fibrous structure is slightly elastic or yielding, and in which direction, also, the strain has 85 none of the powerful leverage which it has at times against the hold of nails or of the rigid angle-pieces. Again, the strain is in such direction that the fastening-strip can be most advantageously and securely fastened to the 90 wall of the trunk, along which it lies, without any liability to work loose, as is the case with the old rigid angle-pieces, and the slight yielding of the fastening-strips, by reason of their own elasticity, to any sudden strain prevents 95 breakage or loosening at the joint.

The form of the strip B may be varied without departing from my invention. Such a variation is shown at C in Figs. 1 and 2, where the strip is twice slit or cut longitudinally at one end, and only one of the three separate ends so formed at that end of the strip is carried between the walls of the trunk and secured to the inner surface of the bottom

wall, the uncut end of the strip being secured to the outer surface of the front wall, and the remaining ends at the cut end of the strip being secured to the outer surface of the bottom wall.

- 5 My improvement is embodied when the canvas or other suitable fastening-strip is so combined with any two walls of a trunk that any part of it passes between those two walls at 10 their junction, and the strip is at the one end secured to the inner surface of one wall, and is at the other end secured to the outer surface of the other wall, and two of such strips are mounted in reverse.
- 15 It is an important advantage of my fastening device that each strip prevents any great motion of the wall of the trunk in the direction tending to loosen the other strip, and cushions and deadens such slight motion as 20 occurs, whereby, also, the strains upon the other strip that might result from a sudden springing back or rebound of the wall of the trunk are avoided.

What I claim as new, and desire to secure by Letters Patent, is—

25 As a fastening device for the walls of trunks, strips of canvas or other suitable fibrous material passing between the walls at their junction, two or more of them at each junction, and drawn taut, and the two secured in reverse, one end of one strip being secured to the inner surface of one wall and the other end to the outer surface of the other wall, and one end of the other strip being secured to the inner surface of the second wall and the other 30 end to the outer surface of the first wall, whereby a securely permanent and tight joint is formed, and any loosening motion of either wall inward or outward at the joint is prevented, substantially as and for the purposes 35 set forth.

GEO. CROUCH.
